UNITED STATES PATENT OFFICE.

HENRY W. HEFFENER, OF YORK, PENNSYLVANIA.

CIGAR-BOX CATCH.

SPECIFICATION forming part of Letters Patent No. 388,868, dated September 4, 1888.

Application filed March 17, 1888. Serial No. 267,535. (No model.)

To all whom it may concern:

Be it known that I, HENRY W. HEFFENER, of York, in the county of York and State of Pennsylvania, have invented certain new and useful Improvements in Catches for Cigar-Boxes, of which the following is a full, clear, and exact description, such as will enable those skilled in the art to which my invention appertains to make and use the same.

10 The object of my invention is to provide for cigar-boxes or analogous receptacles a catch of simple and cheap construction which may be readily applied to the box without cutting away or recessing any portion of it, which will lie flat and close to the surface of the box, so as not to be a source of inconvenience in packing numbers of such boxes together, which will not be liable to become disengaged by the bending or springing inward or outward of 15 the front of the box, and which may be quickly and conveniently operated to secure or to release the lid.

With these objects in view, my invention consists in the construction hereinafter set 20 forth and particularly claimed.

In order to make my invention more clearly understood, I have shown in the accompanying drawings means for carrying the same into effect.

25 In said drawings, Figure 1 is a perspective view of a cigar-box having a catch embodying my invention applied thereto. Fig. 2 is a similar view of a portion of said box, showing the catch disengaged. Fig. 3 is a sectional view 30 of a portion of the box, showing the parts of the catch engaged with each other.

Referring to the drawings, A represents the body of a cigar-box. B is the cover of the same, hinged thereto at b in any ordinary or 40 preferred manner.

C is a plate or escutcheon of sheet metal—such as brass—rigidly secured to the lid B, preferably upon the upper surface thereof. The plate C may be utilized to give an ornamental effect to the cigar-box by stamping said 45 plate out in the form of a fanciful pattern or design, as indicated.

D is a flat tongue depending from the plate C, and lying parallel with and in close proximity to the front of the box and lid. The

lower end of the tongue D is bent upward, as shown, to form an upwardly-pointing lip, d.

Upon the front of the box A is pivoted at e a plate, E, which in material and configuration may be similar to the plate C. The plate 55 E is provided with a flat tongue, F, which is parallel with and rests upon the front of the box, and is carried by the plate when the latter is oscillated upon its pivot e.

G is a stop-pin, which passes through a slot 60 with which the tongue F is provided, which prevents the tongue F from moving in one direction beyond a perpendicular position, and which limits its movement in the other direction to a distance about equal to the width of 65 the tongue.

f is a downwardly-pointing lip formed upon the plate E by bending over its upper end, and situated at such distance from the pivot e as to be in line and engage with the hook d when 70 the tongue F is in a vertical position. When in such position, with the hooks f and d interlocked with each other, it will be seen that the box is securely fastened, the friction between the plate E and the front of the box, 75 which is increased by the engagement of the stop G with the tongue F, serving to prevent any accidental oscillation and disengagement of the lip f.

By reference to Fig. 3 it will be seen that 80 the hooks or lips d f are so engaged with each other that they cannot be separated by any relative movement in lines perpendicular to the front of the box. When it is desired to open the box, the tongue F is moved to the 85 right until arrested by the stop G. The tongue D will then be released, while the tongue F will be maintained in close proximity to its first position, so that a small movement after the lid has been closed will re-engage the lips. 90 The outer tongue is resilient and is normally, when the other tongue is not under it, slightly nearer to the surface of the box than it is when the tongues are engaged, such engagement involving a slight forcing outward of the outer 95 tongue by the inner. The forward edge of the inner tongue at f' operates practically as an inclined plane to effect such result. This insures that the parts of the catch shall not fail to come into their proper relative positions to inter- 100

lock the lips, and that the outer lip shall not lie entirely outside of the inner lip.

Having thus described my invention, what I claim as new, and desire to secure by Letters 5 Patent of the United States, is--

In a cigar-box catch, the combination, with the body A and the lid B, hinged thereto, of the depending tongue D, secured to said lid and provided with the upwardly-extending 10 lip d, the tongue F, pivoted upon the face of the box by the pivot e at right angles to its

surface and provided with the downwardly-extending lip f and the guiding slot, and the stop G, passing through said slot and adapted to limit the oscillation of said tongue F, substantially as described. 15

In testimony whereof I hereunto affix my signature in the presence of two witnesses.

HENRY W. HEFFENER.
